DESIGN FOR A HANDLE FOR A VALVE
OR THE LIKE

Martin J. Rausch, Chicago, Ill., assignor to The
Imperial Brass Manufacturing Company, Chi-
cago, Ill., a corporation of Illinois

Application June 14, 1946; Serial No. 130,689

Term of patent 14 years

(Cl. D91—3)

To all whom it may concern:

Be it known that I, Martin J. Rausch, a citizen of the United States, residing at Chicago, in the county of Cook and State of Illinois, have invented a new, original, and ornamental Design for a Handle for a Valve or the like, of which the following is a specification, reference being had to the accompanying drawing, forming a part thereof.

In the drawing:

Fig. 1 is a plan view of a handle for a valve or the like showing my new design.

Fig. 2 is a side elevational view of the handle shown in Fig. 1 taken from the bottom in that figure.

Fig. 3 is an elevational view of the handle of Fig. 1 taken from the side in that figure.

I claim:

The ornamental design for a handle for a valve or the like, as shown.

MARTIN J. RAUSCH.
